UNITED STATES PATENT OFFICE

CHARLES S. BURTON, OF OAK PARK, ILLINOIS

SUCTION FUEL FEEDING APPARATUS FOR INTERNAL COMBUSTION ENGINES

Application filed September 15, 1930. Serial No. 482,146.

The purpose of this invention is to provide an improved means for moving liquid from a low level source to a place of use adapted particularly for supplying liquid fuel to an internal combustion engine on a motor vehicle having a main fuel supply tank at the rear of the vehicle, creating necessity for lifting the fuel more or less according to the grade of the roadway on which the vehicle may be travelling. It consists in the elements and features of construction and method of operation shown and described as indicated in the claims.

According to the principle of this invention the fuel is to be lifted by suction, derived in some manner from the running of the engine, to a receptacle from which it is to be delivered from the engine carburetor, according to engine requirement; and for such delivery it must be released from the suction by which it has been lifted in order that it may flow by gravity under atmospheric pressure toward the carburetor.

The invention is concerned with the method and means according to and by which the alteration between suction and atmospheric pressure is effected. This method consists in utilizing the weight of the liquid lifted and delivered at each alternation as the motive force for actuating the parts by whose movement the access of atmospheric pressure is effected and interrupted, avoiding the necessity for float or like means commonly employed in vacuum fuel feeding devices for alternating the dominance of suction and atmospheric pressure for the like purpose.

Referring to the drawings:

Figure 1 is a vertical section of an apparatus embodying the invention in one of its forms showing the parts in the position occupied normally when the apparatus is empty of liquid, and the engine is not running.

Figure 2 is a top plan view of the same.

Figure 3 is a section at the line 3-3 on Figure 1.

Figure 4 is a view similar to Figure 1 showing the movable parts at the position occupied when the vacuum chamber is filling due to suction operating therein, and just

before the suction phase is terminated by opening of the atmosphere valve.

Figure 5 is a section at the line 5-5 on Figure 3.

Figure 6 is a detail view like Figures 1 and 4 showing the parts at the position occupied just after the atmosphere valve is opened, and while the liquid is being discharged from the vacuum chamber.

Figure 7 is a view similar to Figure 1 showing a modification.

Figure 8 is a top plan view of the form shown in Figure 7.

Figure 9 is a section at the line 9-9 on Figure 7.

Figure 10 is a section at the line 10-10 on Figure 8.

Figure 11 is a view of the form shown in Figure 7 showing the parts at the position corresponding to that shown in Figure 6 of the first form.

Referring to the form shown in Figures 1 to 6:—The apparatus comprises a casing, 10, which is designed to be mounted in fixed position, as indicated in Figure 1, which shows it mounted at the vehicle dash, S. This casing, 10, is shown comprising a cylindrical shell of sheet metal indicated by the numeral, 11, a top plate member, 12, hereinafter referred to as the cover, and a bottom plate 13, said three parts being united by securing the cover and bottom plate, respectively, to top and bottom flanges, 16 and 17, of the cylindrical member, 11, by screws indicated at 18, a gasket, 19, being interposed to make the bottom joint leakless, this precaution being unnecessary at the top.

The cover, 12, is provided with elbow nipples, 20 and 21, for connecting respectively the fuel supply pipe, 22, and the suction pipe, 23, the former leading from the low level fuel source (not shown) and the latter leading to any source of adequate suction (not shown); and the cover is apertured as seen at 12^x, 12^y, for free atmosphere access.

Both the nipples, 20 and 21, protrude from the under side of the cover, 12, for convenience of connecting to them respectively, flexible tubes, 24 and 25, to be connected at their

65

opposite ends with the container, 40, herein-after described.

The bottom plate carries a discharge fitting, 31, connected to a pipe, 32, for delivering liquid to the place of use,—as, in the case of a fuel feeding apparatus,—the carburetor of the engine served.

Within the casing, 10, there is provided a container, 40, comprising a cylindrical body member, 41, which, as shown, is a cup-shaped sheet metal stamping having its upper margin flanged, as seen at 41^a, for convenience of clamping to it the top plate, 42, by screws, as seen at 42^a, with a gasket, 43, interposed for sealing the joint.

At the bottom of the cup member, 40, it is provided with a discharge fitting, 44, furnished with a valve, 45, normally seating by gravity and related to its seat for being held seated by suction and adapted to be opened by discharge flow of the liquid upon relief of the suction as hereinafter described.

The top plate, 42, has beside the nipples 20^a and 21^a for connecting the flexible tubes, 24 and 25, an opening, 47, of which its margin at the upper side of the plate is finished for seating a valve, 48, hereinafter referred to as the atmosphere valve. Said top plate, 42, has a second opening, 49, at which there is secured, closing said opening, a flexible diaphragm, 50, bound fluid tight at its margin to the margin of the opening, 49, by means of a clamping ring, 51, secured by screws, 51^a.

The atmosphere valve, 48, is formed with a short stem, 48^a, and the diaphragm, 50, is clamped at its central area between discs, 52 and 53, by a threaded stem, 54, with nuts, 54^a and 54^b, above and below the discs, 52 and 53, respectively, for clamping the discs and securing the stem at the center of the diaphragm. At a suitable point on the plate, 42, in line with the valve stem and the diaphragm stem, there is positioned a fulcrum post, 56, for a lever, 57, which is connected at its opposite ends by suitable pivot pins to the valve stem and diaphragm stem respectively, said stems being adjusted in the valve and diaphragm respectively to cause the valve to be held off its seat by the diaphragm flexed inwardly with respect to the cavity of the container, 40, and to be seated when the diaphragm is substantially flat or flexed outwardly an amount of which it is readily susceptible.

The container, 40, is arranged to be guided in up and down movement of which it is susceptible, and for which the length and flexibility of the flexible tubes, 24 and 25, are adapted, by any convenient means as by lugs, 58, 58, 58, set into the edge of the top plate, 42, and spanning the annular interval between the periphery of said top plate and the inner wall of the shell 11.

The upwardly and downwardly movable

container, 40, is yieldingly upheld in the fixed casing, 10, by a spring, 59, arranged for reacting in any convenient place and manner between the two parts, upwardly with respect to the container and downwardly with respect to the fixed shell. As shown, this spring is a helically coiled wire with its upper coil of least diameter seating under the flange, 41^a, of the cup member, 40, and its bottom coil of greater diameter substantially fitting within the shell, 11, at the lower end and seating on the bottom plate, 13.

This spring is dimensioned for being compressed in the assembling of the parts to condition it for resilient reaction to uphold the empty container, 40, to the position shown in Figure 1, and to yield under the weight added by the liquid occupying the container to a predetermined depth, to permit the container to descend to the position shown in Figure 5.

Upon considering the construction as thus far described it may be understood that starting with the apparatus empty, the container, 40, will be upheld by the spring, 59, at the position shown in Figure 1; and upon the engine starting developing suction operating through the suction line and the flexible tube, 25, producing vacuum in the container, 40, fuel will be lifted through the supply line, 22, and delivered through the flexible tube, 24, into the container, 40, causing the latter to be depressed by the added weight of the fuel.

The relative diameters of the valve, 48, and the diaphragm, 50, are calculated in view of the relative lengths of the two arms of the lever, 57, which connects the valve and diaphragm, to cause the suction hold on the valve to slightly exceed the opposing pull of the diaphragm due to the same degree of suction operating on the diaphragm. The valve, 48, is connected by any convenient form of flexible connection, as the light chain, 75, with the cover, 12, of the shell, 11, the connection being preferably made by an interposed resilient part such as the flat spring, 76, secured at one end to the cover plate and having the chain attached to its free end. The chain, 75, is of such length that its slack is entirely taken up in the descent of the container as described; and at the limit of that descent the spring, 76, will be flexed and caused to exert resilient pull on the chain and thereby on the valve, 48.

Upon considering the operation of the structure as thus further described, it may be understood that when the container, 11, is depressed, as described, by the addition to its own weight of the weight of fuel drawn into it, and when that depression has taken up the slack of the chain, 75, the further depression flexing the spring, 76, and bringing its resiliency into operation, when that resilient reaction becomes greater than the suction hold on the valve, 48, due to the slight excess mentioned of the area of the valve

effectively exposed to the suction, over the area of the diaphragm effectively exposed to the same suction, the reaction of the spring will snap the valve open.

When this happens,—requiring a movement of the valve only a distance equal to one-fourth the diameter of the atmosphere port, which, in the construction shown, may be understood to be about $\frac{3}{4}$ of an inch, making the movement for complete opening only $\frac{3}{16}$ of an inch,—the free admission of atmospheric pressure to the cavity of the container, in view of the relative areas of at the atmospheric port and suction port,— $\frac{1}{16}$ of an inch being ample for the latter,—causes the vacuum remaining in the cavity of the container to be negligible for upholding the liquid content under condition of maximum suction necessary for the maximum fuel lift required

10 in the case of a motor vehicle engine having the fuel supply at the rear end; and accordingly; when the atmosphere valve is opened as described, the fuel immediately begins to discharge through the discharge fitting, 44, past the valve, 45, into the casing, 10, and thence by the discharge fitting, 31, and pipe, 32 to the carbureter or other place of use.

15 It may be noted that the retraction of the valve from its seat to the distance for effecting complete opening,— $\frac{3}{16}$ of an inch when the atmosphere port is $\frac{3}{4}$ of an inch in diameter,—will be certain to take place, since as soon as the valve leaves its seat even for a fraction of the full opening movement, the

20 suction hold on the valve will be almost entirely defeated while the suction pull on the diaphragm will be diminished gradually, and will not at any time be entirely lost, and a residual vacuum always remains in the cavity of the container, because the suction port is never closed.

It may be readily calculated that with the relative diameters of the atmosphere port and suction port, atmosphere port $\frac{1}{2}$ inch in diameter, and suction port $\frac{1}{16}$ inch in diameter,—the residual vacuum in the vacuum chamber when the atmosphere valve is fully open, will be only sufficient to sustain about an inch and a half column of gasoline when the vacuum due to engine suction with the atmosphere valve closed is that measured by 6" hg; and the device will be fully operative for maximum fuel lift required in supplying an engine on a motor vehicle from a rear tank for which vacuum of 3" hg. is sufficient, with an atmosphere port $\frac{1}{2}$ inch in diameter if the depth of the chamber in which the liquid is accumulated, from a level at which the fuel load is adequate to overcome the resiliency of the supporting spring, down to the level of discharge past the valve, 45, exceeds one inch. That is to say, under these circumstances, the liquid will be discharged from the vacuum chamber to within about an inch

of the level at which the discharge occurs past the valve, 45.

By making the atmosphere port $\frac{3}{4}$ of an inch as shown in the drawings, and correspondingly enlarging the diaphragm, 50, the margin of residual vacuum will be reduced and the depth which will not be discharged will be correspondingly reduced so as to be negligible. And it is considered entirely practicable to make the atmosphere port one inch in diameter, since the diaphragm may be correspondingly enlarged so as to counter-balance the suction hold to the narrow margin desirable for ready opening of the valve, particularly because, the larger the diaphragm the less the flexure necessary for reacting on the valve, and the less the liability of deterioration of the diaphragm.

Under conditions of engine operation making the vacuum due to engine suction when the atmosphere valve is closed that measured by 6" hg, it may be readily calculated that with the atmosphere port enlarged to one inch diameter and the suction port retained at $\frac{1}{16}$ of an inch, which is ample, the height of gasoline column which will be upheld by the residual vacuum when the atmosphere valve is open, is reduced to about 1/200 of an inch, —practically zero.

Upon considering the operation of this apparatus when it is connected for supplying an engine carbureter, it will be understood that whenever the fuel supply exceeds the engine requirement, the fuel will accumulate first in the pipe, 32, filling it up to the connection with the container, 10, and then if the supply continues to exceed the engine consumption, the fuel will accumulate in the cavity of the container, 10, up to the discharge valve, 45, and then still upward around the inner movable container, 40. And when this condition arises and continues, it will come to pass that in some instances of emptying of the container, 40, the outflow from that chamber will raise the level of liquid in the casing chamber to the lowered level of the inner container; and thereupon, a balance of static pressure being created, the descent of the container will be halted, with the atmosphere valve open; and no further fuel lifting action will occur until engine consumption lowering the level of the fuel in the casing chamber, permits the container to descend to the limit of its range of movement and close the atmosphere valve so as to re-establish a condition of suction.

In Figures 6, 7 and 8 there is shown a modification of this invention designed for avoiding the use of the flexible tubes for connecting the suction pipe and fuel pipe nipples of the fixed outer container with the movably mounted yieldingly upheld inner container which constitutes the vacuum chamber and liquid accumulating chamber.

In this modification the fixed outer casing,

A, for enclosing the main cavity shown as of sheet metal stamping in cup form, has the cover plate, A¹, bound fluid-tight to the body member, as indicated by the gasket, a¹, interposed between the upper end flange, a, of the cylindrical body member, A, and the shoulder of the cover plate against which it is bound by the screws, a¹⁰.

The cover plate has a nipple, a⁵, for connecting the fuel supply pipe indicated at A⁵, and a nipple, a⁶, for connecting the suction pipe indicated at A⁶, the latter having restricted suction port, as seen at a⁶⁰.

The cover plate has beside the fuel and suction connections, an atmosphere inlet port, a⁸, marginally finished at the upper side of the cover plate for seating the atmosphere valve, A⁸, and an aperture, a⁹, closed by a flexible diaphragm, A⁹, said atmosphere port and valve being dimensioned relatively to the diaphragm-closed aperture and diaphragm, as described with respect to the like elements and features of the construction shown in the earlier described figures.

The diaphragm, A⁹, and valve, A⁸, are connected as in the earlier figures by a lever, A⁴, fulcrumed on a depending post, A¹⁰, and connected at one end to the stem, a¹⁸, of the valve, A⁸, and the other end to the stem, a¹⁹, of the diaphragm, A⁹.

The bottom plate, A², has a centrally mounted hollow-stemmed discharge fitting, A²⁰, furnished with a discharge valve, A²¹, arranged to be normally seated, and to be opened by the discharge flow; and attached to the under side of the bottom plate, A², there is secured by liquid-tight joint, as indicated by the gasket, a²¹, a hood, A¹², constituting an addition to the casing, A, and whose cavity constitutes a liquid receiver chamber and has connected to it a fuel delivery pipe, A¹³, leading to the engine carburetor or other place of use.

Within the outer casing, A, there is mounted for limited up and down movement an upwardly open fuel receiver, B, whose open upper end mouth is overhung by the fuel supply nipple, a⁵, so that fuel drawn in through the fuel supply pipe by suction is discharged into the fuel receiver, B.

This element, which may also be referred to as the vacuum chamber since its cavity constitutes the essential part of the chamber in which vacuum is produced for indrawing of the fuel,—is guided in its up and down movement by lugs, b, b, b, mounted exteriorly at convenient position, and by a discharge nipple, B¹, with which the fuel receiver is terminated at the center of its bottom, and which is dimensioned for telescoping in the hollow stem of the discharge fitting, A²⁰.

The fuel receiving chamber, B, is upheld in the casing, A, by a spring, D, similar to the spring, 59, of the first described form, said spring being dimensioned suitably for

being conditioned in assembling the parts so that it will uphold the empty fuel receiver, A, and will yield to allow the same to descend a predetermined distance under the load of liquid accumulated in it to a predetermined depth, and will react to restore the receiver, A, to fully elevated position upon discharge of its fuel load.

In this construction the atmosphere valve, A⁸, normally seated by gravity and the reaction of the diaphragm, A⁹, to its normally flat form, is operative for opening by the descent of the container, B, under full load of fuel, by means of a flexible connector, as the chain, B², which is connected at one end to the stem of the diaphragm, A⁹, and at the other end to the free end of the flat spring, B³, secured at its other end to the container, B; and the atmosphere valve is closed in the rising movement of the container, B, by the encounter of a stud, b⁴, screwed into a bracket lug, B⁴, mounted on the container for encounter of the end of the lever, A⁴, to which the diaphragm A⁹, is connected, said stud being adjustable by screwing up or down to give the proper action at the proper point in the rising movement of the container, B, as it is relieved of the load and conditioned for yielding to the reaction of the spring.

The casing member described as the hood, A¹², has connected with it and constituting a part of the fixed casing, a standpipe, A¹⁵, which extends upwardly alongside the main casing member, A, and is open to atmosphere at a point above the high liquid level of the container, B,—that is, the highest level to which the container is occupied by liquid when it is thus loaded to the degree for overcoming the resistance of the supporting spring, D, and is thereby caused to descend and operate the atmosphere valve for opening to relieve the vacuum and cause the delivery of the liquid to the chamber afforded by the hood, A¹².

Upon considering these modified features in comparison with the first described form, it may be recognized that the principle of construction and operation is substantially the same in both forms, but that in the second described form, the chamber in which the vacuum is produced includes the entire cavity of the outer shell, A, as well as the cavity of the upwardly open cup member, B, therein; and that in this second form the liquid cannot at any stage in the proper operation of the structure enter the cavity of the casing outside the upwardly open container, B, unless leak should occur at the telescopic connection of the discharge nipple, B¹, with the discharge fitting, A²⁰; and the liability to such leakage may be rendered negligible by dimensioning the nipple and the bore of the stem of the discharge fitting for easy sliding of the nipple in the stem, because by reason of the flow capacity of the nipple, being

slightly greater than the flow capacity of the discharge connection of the hood, A¹², with the pipe, A³, thereby preventing the liquid flowing out of the hood as fast as it flows in, during the liquid discharge phase of the operation of the apparatus, the hood cavity will be filled with liquid which provides a liquid seal for the telescoping joint sufficient to prevent any leak during the suction phase; and 10 when the supply of fuel delivered exceeds the engine use, so that there is an accumulation in the standpipe, no disadvantage will result from any leakage of liquid which might occur through the telescoping joint into the cavity of the casing, A, and on the contrary, there will be some advantage resulting from the limited leaking of liquid back into the chamber because it would insure the maintenance of liquid seal preventing 15 the defeat of the vacuum.

But in any event in the construction as illustrated, the discharge fitting, A²⁰, with the flow passage leading to the valve, A²¹, is U-shaped, and with the upwardly trending discharge limb, of the U-form extending a substantial distance above the level to which the discharge end of the discharge nipple, B¹, of the fuel receiver, B, will be withdrawn at the highest position of the part, B, so that the telescoping joint between the nipple and the fitting, A²⁰, will always be liquid sealed after the first emptying operation of the vacuum chamber, the fuel receiver, B.

I claim:

1. A construction for moving liquid from a source at a lower level to a higher level and delivering it by gravity to a place of use comprising a chambered casing; a liquid container enclosed in a chamber of the casing and movable up and down therein, and means for yieldingly supporting it at predetermined position therein; means affording and controlling suction connection atmospheric access and liquid inflow to said container, the container being depressed against the resistance of the yielding upholding means by the weight of liquid drawn into the container while the atmosphere access is closed, the casing having a second chamber into which the container discharges; a discharge fitting through which the container discharges provided with a valve opening for discharge and normally closed and adapted to be held closed by suction operating in the container cavity.

2. The construction defined in claim 1, the casing chamber in which the container discharges having extent in which liquid may rise to a point above the level to which the container is loaded with liquid thereby overcoming the resistance of the yielding upholding means, and having continuously open atmosphere access above that level.

3. A construction for moving liquid to a higher level from a source at a lower level and delivering it by gravity to a place of use

or accumulation, comprising a liquid container into which the liquid is drawn from the lower source and in which it is retained against gravity discharge by suction due to vacuum in the cavity of the container, said 70 container having connection constituting access for suction and means for air outlet to a source of suction, and independent connection for liquid inflow from the liquid source, said container being constructed and arranged for discharge of liquid therefrom by gravity upon relief of the suction, and being mounted for up-and-down movement, and yielding means by which said container is yieldingly upheld at a predetermined position, said container having also access for atmospheric pressure and means for alternating the dominance of suction and atmospheric pressure in the container cavity said 80 means comprising an element arranged for 85 actuation in one direction in the movement of the container due to its weight plus that of the liquid content thereof exceeding the resistance of the yielding upholding means, and in the other direction by the reaction of 90 said means upon the delivery of the liquid from the container relieving it of said plus weight, comprising a casing in fixed position and encompassing the container and having a chamber into which the container chamber discharges, said casing chamber being 95 open to atmosphere at a point above the level to which liquid occupies the container chamber for overcoming the yielding supporting means, the casing having at fixed position 100 connections for attaching a liquid supply conduit and a suction conduit, and flexible duct members within the casing chamber leading from said fixed connections respectively for connection with the movable container for access thereto of suction and liquid respectively.

4. In a container for moving liquid from a source at a lower level to a higher level and delivering it by gravity to a place of use comprising a container having a liquid accumulating chamber with liquid inflow connection with the low level source and liquid outflow connection with the place of use; a casing having a chamber within which said container is supported, said casing being mounted in fixed position; means by which the container is yieldingly supported by the casing, the container having connection with a source of suction and having an atmosphere inlet at the upper part and a valve controlling said inlet; means causing the atmosphere valve to be intermittently closed while the suction connection is open at the normal position of the parts when the container and casing chambers are both empty of liquid; whereby suction from a suction source causes liquid to be accumulated in the container chamber and to depress it by gravity in opposition to the yielding supporting 120 means.

means, the casing having a second chamber connected for discharge of the container thereinto with valve means controlling said discharge and preventing discharge during the suction phase and preventing reverse flow at all times, the casing having a standpipe extending from the last mentioned casing chamber upwardly to a point above the predetermined level to which the container will be filled in accumulating weight of liquid sufficient for depressing it in opposition to the yielding upholding means; whereby liquid delivered to the second mentioned casing chamber in excess of delivery therefrom to the place of use accumulating in the standpipe to said predetermined height operates to halt the discharge of the liquid from the container and halt its descending movement and prevent closure of the atmosphere port and the re-establishment of predominance of suction until engine consumption at the place of use lowers the level of liquid in the standpipe.

5. The construction defined in claim 1, the casing having the means for atmosphere access consisting of an opening in its wall, and the valve controlling atmosphere access being seated at said opening, the container being upwardly open in the casing chamber, and said chamber being without atmosphere access except at said valve-controlled opening, the casing having a suction connection, and having connection for liquid inflow at the upper part at a point for discharge of the liquid into the open upper end of the container.

6. A construction for moving liquid to a higher level from a source at a lower level and delivering it by gravity to a place of use or accumulation, comprising a liquid container into which the liquid is drawn from the lower source and in which it is retained against gravity discharge by suction due to vacuum in the cavity of the container, said container having connection constituting access for suction and means for air outlet to a source of suction, and independent connection for liquid inflow from the liquid source, said container being constructed and arranged for discharge of liquid therefrom by gravity upon relief of the suction, and being mounted for up-and-down-movement, and yielding means by which said container is yieldingly upheld at a predetermined position, said container having also access for atmospheric pressure, and means for alternating the dominance of suction and atmospheric pressure in the container cavity, said means comprising an element arranged for actuation in one direction in the movement of the container due to its weight plus that of the liquid content thereof exceeding the resistance of the yielding upholding means, and in the other direction by the reaction of said means upon the delivery of the liquid from the container relieving it of said plus weight, a casing structure having a cavity in which said container is enclosed, said cavity being in fluid pressure communication with the cavity of the container, the connection of the container for suction and atmosphere access being afforded by suction and atmosphere connections with which said enclosing casing is provided, said casing having at the bottom a discharge fitting with a passage opening at one end in said cavity of the casing and at the other end outside said cavity, and at said outer end provided with a valve arranged to be normally seated and adapted to be opened by fluid discharge from the fitting, the container having at the bottom a discharge nipple arranged to telescope in the entrance to the passage of said fitting, the casing comprising a part having a second cavity in which the valve discharge fitting is enclosed and discharges, said casing part being arranged for having a liquid delivery

from the container relieving it of said plus weight, an enclosing casing whose cavity is at all times in fluid pressure communication with the cavity of the container, the connection of the container for suction and atmospheric access being afforded by suction and atmospheric connections with which said enclosing casing is provided, the container having a liquid discharge nipple at the bottom, the casing having at the bottom an opening and a fitting closing said opening, and having a guide bearing for said discharge nipple in which the latter is fitted for reciprocating substantially without air leak.

7. A construction for moving liquid to a higher level from a source at a lower level and delivering it by gravity to a place of use or accumulation, comprising a liquid container into which the liquid is drawn from the lower source and in which it is retained against gravity discharge by suction due to vacuum in the cavity of the container, said container having connection constituting access for suction and means for air outlet to a source of suction, and independent connection for liquid inflow from the liquid source, said container being constructed and arranged for discharge of liquid therefrom by gravity upon relief of the suction, and being mounted for up-and-down movement, and yielding means by which said container is yieldingly upheld at a predetermined position, said container having also access for atmospheric pressure, and means for alternating the dominance of suction and atmospheric pressure in the container cavity, said means comprising an element arranged for actuation in one direction in the movement of the container due to its weight plus that of the liquid content thereof exceeding the resistance of the yielding upholding means, and in the other direction by the reaction of said means upon the delivery of the liquid from the container relieving it of said plus weight, a casing structure having a cavity in which said container is enclosed, said cavity being in fluid pressure communication with the cavity of the container, the connection of the container for suction and atmosphere access being afforded by suction and atmosphere connections with which said enclosing casing is provided, said casing having at the bottom a discharge fitting with a passage opening at one end in said cavity of the casing and at the other end outside said cavity, and at said outer end provided with a valve arranged to be normally seated and adapted to be opened by fluid discharge from the fitting, the container having at the bottom a discharge nipple arranged to telescope in the entrance to the passage of said fitting, the casing comprising a part having a second cavity in which the valve discharge fitting is enclosed and discharges, said casing part being arranged for having a liquid delivery

pipe connection from the last mentioned casing cavity, and a standpipe extending from said cavity to a point above the level to which the container is filled with liquid for weighting it to overcome the yielding up-holding means.

In testimony whereof, I have hereunto set my hand at Chicago, Illinois, this 13th day of September, 1930.
